UNITED STATES PATENT OFFICE.

ARTHUR REGINALD ANGUS, OF SPIT ROAD MOSMAN, NEW SOUTH WALES, AUSTRALIA.

DEVICE FOR PREVENTING COLLISIONS BETWEEN TRAINS.

1,218,970.

Specification of Letters Patent. Patented Mar. 13, 1917.

Application filed December 27, 1909. Serial No. 534,936.

To all whom it may concern:

Be it known that I, ARTHUR REGINALD ANGUS, a subject of the King of Great Britain, residing at Spit Road Mosman, 5 formerly of Barry Street Neutral Bay, in the State of New South Wales and Commonwealth of Australia, solicitor, have invented new and useful Improvements in and Relating to Devices for Preventing Collisions Between Railway-Trains, of which the following is a specification.

This invention forms one of a series devised by the same inventor for the protection of trains and has for object to eliminate as far as practicable the risk of collision between railway trains.

The invention relates particularly to automatic train protecting systems of the type in which a train, on effecting contact with 20 certain track contacts (hereinafter called controlling track contacts), is enabled electrically to render other track contacts, placed either ahead of it, or behind it, or both, operative to produce a danger indication on a conflicting train.

By means of apparatus according to the invention a train is automatically given a danger indication if, on effecting contact with a controlling contact, it fails to send 30 out current sufficient for operating a switching instrument by which distant track contacts are rendered operative to produce a danger indication on a conflicting train. By this means a train is prevented from proceeding if, due to failure of its own, or the 35 track, apparatus, it is unable to set correctly track apparatus for securing its own safety while proceeding on its journey.

The various features of the invention are 40 hereinafter set out in the claims appended hereto and in order to explain clearly how this invention is carried into effect the construction of train protecting apparatus according to this invention, of the type above 45 referred to, and the operation thereof are hereinafter described with reference to the accompanying drawings:—

Figure 1 is a diagrammatic view of the 50 apparatus carried by a train and of certain of the track contacts. Fig. 2 is a view showing a set of contact devices carried by a train. Fig. 3 is a diagrammatic view of the track contacts and appurtenant apparatus of a single railway track adapted to enable 55 trains to run in both directions thereon. Fig. 4 is a diagrammatic view illustrating a modification of the apparatus shown in Fig.

3 wherein the coils of switching instruments which are to be operated simultaneously from the same track contacts are connected in parallel with one another instead of in series. Fig. 5 is a diagrammatic view of the track contacts and appurtenant apparatus of double railway tracks on each of which trains only run in one direction, one 60 track being for down trains only and the other for up trains only.

In the example of apparatus shown in Figs. 1 and 2 of the drawings sets of contact devices (Fig. 2) corresponding to three 70 separate sources of electricity are arranged beneath the locomotive and are illustrated diagrammatically at *a*, *b*, and *c* in Fig. 1. The contact devices 78, 79, 80, 81, 081, 080, 079, and 078 (Fig. 2) of each of these sets 75 are carried in cylindrical casings, mounted on a bracket 77 attached firmly to the frame of the locomotive, and are provided at their lower ends with friction rollers (brushes or the like) to make contact with the track 80 contacts arranged along the tracks, springs being provided to press the contact devices against the track contacts.

The contact devices 78 and 078 are connected respectively by wires 83 and 84 to 85 corresponding contacts 85 and 86 of what is hereinafter called the "commutator switch," the handle 96 of this switch being located in the cab 5 of the locomotive so as to be easily 90 reached by the driver when necessary and for the purposes hereinafter mentioned.

The contact devices 79 and 079 are similarly connected by wires 88 and 89 respectively to corresponding contacts 90 and 91. The contacts 85, 86, 90, 91 have corresponding contact arms 92, 93, 94, and 95 respectively which are all connected to a common handle 96 so as to be adapted to be simultaneously moved thereby. The contact arms 92 and 93 are connected by wires 98 and 99 100 respectively to the spring contacts 100 and 101 respectively of what is hereafter called the "reversing gear switch" the movable part 1 of which has a connection 2 with the reversing gear 3 of the locomotive so as to 105 be moved thereby. Similarly the contact arms 94 and 95 are connected by wires 103 and 104 to spring contacts 105 and 106 of the reversing gear switch. The contact plates 111 and 112 are carried by but insulated from the movable part of this switch 110 and are adapted to effect contact with either the corresponding contacts 100 and 101, or the corresponding contacts 105 and 106,

when the reversing gear 3 of the locomotive is moved into one or other of its extreme positions.

There are three contacts 100 and 105 and 5 111 insulated from one another. The three contact blocks 111 are connected to a dynamo 118, accumulators 126 and a primary battery 127 by wires 116, 124, and 125 respectively while the three contact blocks 100 and 105 10 are connected through the commutator switch either to the contact devices 78 shown at *a*, *b*, and *c* respectively or to the contact devices 79 shown at *a*, *b* and *c* respectively.

15 The contact 112 is connected by wire 117 to the dynamo 118, and by wire 117 and corresponding wires 128 and 129 to the accumulators 126, and the primary battery 127 respectively.

20 If the dynamo generates current the electromagnet 121 included in the wire 116 is energized and attracts its armature 123 thus breaking at the contacts 133 and 135 the circuits of the wires 124 and 125 and so 25 disconnects the accumulators 126 and primary battery 127 respectively from their corresponding contacts 111.

If the dynamo, which may be driven in any desired manner such as by a belt or 30 the like from an axle of the locomotive or by an auxiliary steam engine, fails to generate current the accumulators 126 come into action, the electromagnet 130 included in the wire 124 attracting its armature 122 and 35 breaking the circuit of the wire 125 from the primary battery 127 at contacts 134 and the electromagnet 131 breaking the circuit of wire 116 connected to the dynamo 118 at contacts 119.

40 Similarly if both the dynamo 118 and the accumulator 126 fail to generate current as required the primary battery 127 comes into operation, the electromagnets 136 and 137 included in the wire 125, breaking the circuits of the accumulators 126 at the contacts 45 132 and of the dynamo 118 at the contacts 119 respectively.

The contact device 81 is connected by wire 141, electromagnet 143, solenoid 144, battery 50 145 to contact device 081. The electromagnet 143 when energized by the bridging of the contact devices 81 and 081 attracts its armature 146 and thereby operates a miniature signal 148, while the solenoid 144 when 55 energized attracts its plunger and operates the rod 147 so as to cause the whistle 150 to be blown.

The signal 148 when set to danger bridges the contacts 152 and 153 and so completes 60 the circuit 154 of an electric bell 155 and battery 156.

The contact device 80 is connected by wires 157, 162, electromagnet 163, wire 162, battery 145, wire 141, solenoid 172, solenoid 65 171, wire 170 and wire 158, to contact de-

vice 080. When the solenoid 172 is energized by the bridging of the contact devices 80 and 080 its plunger 174 is attracted and moves the steam throttle lever 176 to shut off steam from the locomotive, while the solenoid 171 when energized attracts its plunger 173 and operates the brake lever 175 to apply the brakes. The electromagnet 163, when energized, attracts its armature 164 so as to bridge, with its contact piece 165, the contacts 160 and 161, connected to the wires 157 and 158 and thereby to maintain the circuit of the solenoids 171 and 172 closed after circuit has been broken at the contact devices 80 and 080. In this manner 70 a stopping operation is maintained on the train after the train itself has passed out of contact with the track contact which originally produced the stopping operations. The armature 164 is provided with a handle 75 4 located in the cab 5 of the locomotive so as to break contact at the contacts 160 and 161 and thereby to prevent the continuance of the stopping operations when desired.

The functions of the reversing gear switch 90 and the commutator switch are to connect the generator (either dynamo 118, accumulators 126, or battery 127) to either the inner contact devices 79, 079 or the outer contact devices 78, 078 according to the direction in which the train is running, trains running on the down journey always having their generators connected to the contact devices 78, 078 and trains running on the up journey always having their generators connected to the contact devices 79, 079. 95

The reversing gear switch serves to change the connections of the generator from 78, 078 to 79, 079 or from 79, 079 to 78, 078, when the direction of motion of the 100 train is reversed by moving the reversing gear of the locomotive, while the commutator switch, when operated by the driver, performs the same operation when the direction of running of the train is changed 105 by turning the locomotive around.

It will be noticed that when the reversing gear and the commutator switches have both 110 been operated and the train is therefore running in the original direction the connections of the generator to the contact devices 78, 078 or 79, 079, as the case may be, remain unaltered.

In Fig. 3 is shown a section of single track and the track contacts and appurtenant apparatus thereof. At intervals along the track are arranged sets of track contacts, each set consisting of outer controlling contacts 40, 040, inner controlling contacts 41, 041, stop contacts 42, 042 and 120 warning contacts 43, 043. Each set of contacts is provided with a switch 44 the moving part 54 of which is operated by electromagnets 55 and 56 connected with and 125 energized by contact of a train with outer 125

controlling contacts 40, 040, and with a similar switch 044 connected with and operated by contact of a train with inner controlling contacts 41, 041. Each set is also provided 5 with a switch 45, the moving part of which is operated by two solenoids which are connected respectively to the outer and to the inner controlling contacts of the set. Each of these switches 44, 044 and 45 is adapted 10 electrically to connect or disconnect from each other the warning contacts 43, 043 and the stopping contacts 42, 042 of the set. The switch 45 normally connects, by means of its contact 71, the contacts of each pair through 15 wire 180, wire 192, contact 72, contact 73, wire 193, and wire 181 for stopping contacts 42, 042, and through wire 186, wire 192, contact 72, contact 73, wire 193, and wire 187 for warning contacts 43, 043, and disconnects 20 them only when energized. The switch 44, when moved into a position in which its armature 54 contacts with contacts 58 and 59 connects stopping contacts 42, 042 together through wire 180, wire 192, 25 contact 58, contact 59, wire 193 and wire 181, and connects warning contacts 43, 043 together through wire 186, wire 192, contact 58, contact 59, wire 193, and wire 187. The switch 044 operates in a manner similar to 30 the switch 44.

Other sets of track contacts (hereinafter referred to as "rear" sets) are located alternately with the sets mentioned above, each of these sets consisting of stop contacts 46 35 and 046 and warning contacts 47, 047, which are adapted to be electrically connected with or disconnected from each other by corresponding switches 48 and 048 as hereinafter described by way of example in regard to a 40 train effecting contact with the outer controlling contacts 40 and 040 at C.

It will be seen that when a train equipped with the apparatus described with reference to Figs. 1 and 2 comes into contact with a 45 pair of warning or stopping contacts which are electrically connected together by a corresponding switch the circuit of the battery 145 on the train is completed through either warning apparatus, or stopping apparatus, 50 on the train, so that warning, or stopping, operations are brought about on the train as hereinbefore described. If, however, the warning, or stopping, contacts are not electrically connected together the circuits of 55 the apparatus on the train will not be completed by contact of the train with these track contacts and consequently warning or stopping operations will not be brought about on the train. It will also be seen that a 60 train, on coming into contact with controlling track contacts 40, 040 or 41, 041, will send current through either the one pair or the other pair of contacts according to the direction in which the train is traveling, so that a 65 train performing a journey in one direction

is enabled to operate one set of switching instruments say 44, 48 while a train performing a journey in the opposite direction is enabled to operate the other set of switching instruments 044, 048.

When a train performing say a down journey, that is to say, in the direction A B C D E, effects contact by means of its contact-devices 78, 078 with outer controlling contacts 40 and 040 at C, and current flows 75 from the generator on the train (which may be either the dynamo 118, the accumulator 126, or the battery 127) it will pass as hereinbefore described through the apparatus on the train, controlling contact 40 at C, wire 80 178, electro-magnet 56 of switch 44 at C, electro-magnet 55 of switch 44 at E and wire 179 back to the train through contact 040. Current will also pass from contact 40 by wire 182, electro-magnet 55 of switch 48 between 85 B and C, electro-magnet 56 of switch 48 (not shown) just before A and back to the train through contact 040. Current moreover also passes from contact 40, wire 178, coil of switch 45, and back to the train 90 through contact 040.

The contact of a train with a pair of controlling contacts 40, 040 thus produces, if current flows from the train, (1) the attraction of the armature 54 of 44 at E by the 95 electro-magnet 55 and the consequent connection together of the warning contacts 43, 043 and the stopping contacts 42, 042 at E thus preventing another train traveling in the opposite direction from passing E; (2) 100 the attraction of the armature 54 of 44 at C by the electromagnet 56 and the consequent disconnection there of the warning contacts 43, 043 and of the stopping contacts 42, 042 at C; (3) the attraction of the armature of 105 48 between B and C by the electro-magnet 55 into such a position that the corresponding warning and stopping contacts are rendered operative to produce warning and stopping operations respectively on a following train coming into contact therewith; (4) the attraction of the armature of a switch 48 (not shown); just before A, by an electro-magnet 56 into such a position 110 that the corresponding warning and stopping contacts are rendered inoperative to produce warning and stopping operations respectively on a following train coming into contact therewith; and (5) the attraction of the plunger of the switch 45 and so 115 breaks the electrical connections there between the corresponding warning contacts 43, 043 and stopping contacts 42, 042.

The operation set forth of the switches 44 and 45 at C which are effected just before 125 contact of the train with the warning contacts 43, 043 prevent warning and stopping operations from being effected on the train on contact with the contacts 43, 043 and 42, 042 of the same set.

It will therefore be seen that a train, on effecting contact with controlling track contacts, sets a distant instrument ahead and a near instrument behind it into danger positions for a conflicting train and at the same time sets a more remote instrument behind it into the clear position and instruments, relating to a set of contacts comprising the controlling contacts with which it is in contact, into clear positions.

The train is enabled to proceed only if it passes current through controlling contacts with which it is in contact and thereby energizes the switch 45 and if the corresponding switch 44 has been set into the clear position—that is to say, if current for setting a distant switch 44 ahead of the train into the danger position for another train has been sent into the controlling contacts and through the circuit corresponding to the switching instruments to be operated. If, therefore, all the generators on the train for operating track instruments should fail or if the train for any other reason fails to pass through a controlling track contact current sufficient for operating the corresponding instruments the train will be automatically prevented from proceeding on its journey.

Similar operations to those above described take place when a train comes into contact with other controlling contacts at A, B, D, and E on the down journey.

On the up journey the operations performed are also similar to those above described with the differences that the train sends out current through the contact devices 79, 079 and the inner controlling track contacts 41, 041 and operates switching instruments 044 and 048 instead of 44, 48.

The arrangement shown in Fig. 4 is similar to that shown in Fig. 3 with the exception that instead of connecting the coils of the switching instruments 44 or 044 which are to be operated simultaneously, in series, they are connected in parallel, the operation of the apparatus being substantially the same in both cases.

Each train should be fitted with some continuous automatic brake.

The distance apart of any two nearest stop contacts, say stop contacts 42 and 042 at B (Fig. 1) and stop contacts 42 and 042 at C (Fig. 3), should be such that any two trains running at their limits of speed permitted may be stopped before colliding if steam be shut off and brakes applied by each when one train is passing over stop contacts 40 and 040 at B and the other train 40 and 040 at C and so on throughout the journey.

Again the stop contacts 46 and 046 should also be a similar safe distance away from the controlling track contacts 40, 040 or 41, 041 from which they are rendered operative so that when one train is on say the outer controlling contacts 40, 040 at C a following

train may be stopped after passing over the stop contacts 46 and 046 between B and C before arriving at the position occupied by the train it is following.

What I claim is:—

1. In a railway signaling system, a series of block sections, in each of said block sections track controlling means, a first signaling means, means for enabling said first signaling means to be rendered operative by means of a said controlling means located in the next but one of said block sections behind, means for enabling said first signaling means to be rendered inoperative by means of a said controlling means in its own section, a second signaling means located behind the last mentioned controlling means, means for enabling said second signaling means to be rendered operative by means of the last mentioned controlling means, and means for enabling said second signaling means to be rendered inoperative by means of a said controlling means located in front of the last mentioned controlling means, and on a train, danger-indicating means, signal transmitting means adapted to coöperate with said signaling means on the track and to operate said danger-indicating means when coöperating with a said signaling means located on the track and rendered operative as aforesaid, and controlling means adapted to coöperate with said track controlling means to render said signaling means operative and inoperative as aforesaid. 70 75 80 85 90 95 100

2. In a railway signaling system, a series of block sections, in each of said block sections track controlling means, a first fixed signaling means, means for enabling said first signaling means to be rendered operative by means of a said controlling means located in the next but one of said block sections behind, means for enabling said first signaling means to be rendered inoperative by means of a said controlling means in its own section, a second fixed signaling means located behind the last mentioned controlling means, means for enabling said second signaling means to be rendered operative by means of the last mentioned controlling means, and means for enabling said second signaling means to be rendered inoperative by means of a second controlling means located in front of the last mentioned controlling means, and on a train, danger-indicating means, signal transmitting means adapted to coöperate with said signaling means on the track and to operate said danger-indicating means when coöperating with a said signaling means located on the track and rendered operative as aforesaid, and controlling means adapted to coöperate with said track controlling means to render said signaling means operative and inoperative as aforesaid. 105 110 115 120 125 130

3. Train protecting apparatus comprising in each block section a pair of controlling track contacts, a pair of indicating track contacts, electro-magnetic means adapted when energized to connect together electrically the contacts of said pair of indicating track contacts, electrical connections permanently connecting said electromagnetic means between the contacts of a said pair of controlling contacts located in the next but one block section in the rear, a second electromagnetic means adapted when energized to disconnect the contacts of said pair of indicating track contacts, electrical connections 5 permanently connecting said second electromagnetic means between the contacts of the first mentioned pair of controlling contacts, a second pair of indicating track contacts, a third electromagnetic means adapted when energized to connect together electrically the contacts of said second pair of indicating track contacts, electrical connections permanently connecting said third electromagnetic means between the contacts of a said pair of controlling contacts located in a block section in advance, a fourth electromagnetic means adapted when energized to disconnect the contacts of said second pair of indicating track contacts, electrical connections 10 permanently connecting said fourth electromagnetic means between the contacts of a said pair of controlling contacts located farther in advance than the last mentioned pair of controlling contacts, and on a train contacting means adapted to come into contact with each pair of said controlling contacts and thereby to complete electrical circuits through the aforesaid electromagnetic means connected thereto and located in the block section in question and in block sections in the rear and in advance thereof, and a danger indicating device adapted to come into contact with and be operated by each of said signaling means 15 rendered operative as aforesaid. 70
4. Train protecting apparatus comprising a pair of controlling track contacts, a pair of indicating track contacts located remote from said controlling contacts, a generator of electricity, an electromagnetic device adapted when operated to render said indicating contacts operative, contacting means carried by a train and adapted to effect contact with said controlling contacts, an electric circuit including said generator and said electromagnetic device and adapted to be completed, by contact of said contacting means with said controlling contacts, so as to operate said electromagnetic device and thereby to render said indicating contacts 20 operative, a second pair of indicating track contacts, contacting means carried by said train and adapted to come into contact with said second pair immediately after the aforesaid contacting means effects contact with said controlling contacts, and a second electromagnetic device included in said circuit 25 in series with the first mentioned electromagnetic device and adapted to be energized by the current sent through said circuit and to be operated by such current so as to render the last mentioned pair of indicating contacts inoperative only when such current is sufficient for operating the first mentioned electromagnetic device. 110
5. Train protecting apparatus comprising a pair of controlling track contacts, a pair of indicating track contacts located remote from said controlling contacts, a generator of electricity, an electromagnetic device adapted when operated to render said indicating contacts operative, contacting means carried by said train and adapted to effect contact with said controlling contacts, an electric circuit including said generator and said electromagnetic device and adapted to be completed, by contact of said contacting means with said controlling contacts, so as to operate said electromagnetic device and thereby to render said indicating contacts operative, a second pair of indicating track contacts, contacting means carried by said train and adapted to come into contact with said second pair immediately after the aforesaid contacting means effects contact with said controlling contacts, and a second electromagnetic device included in said circuit in series with the first mentioned electromagnetic device and adapted to be energized by the current sent through said circuit and to be operated by such current so as to render the last mentioned pair of indicating contacts inoperative only when such current is sufficient for operating the first mentioned electromagnetic device. 115
6. Train protecting apparatus comprising a pair of controlling track contacts, a pair of indicating track contacts located remote from said controlling contacts, a generator of electricity located on a train, an electromagnetic device adapted when operated to render said indicating contacts operative, contacting means carried by said train and adapted to effect contact with said controlling contacts, an electric circuit including said generator and said electromagnetic device and adapted to be completed, by contact of said contacting means with said controlling contacts, so as to operate said electromagnetic device and thereby to render said indicating contacts operative, a second pair of indicating track contacts, contacting means carried by said train and adapted to come into contact with said second pair immediately after the aforesaid contacting means effects contact with said controlling contacts, and a second electromagnetic device included in said circuit in series with the first mentioned electromagnetic device and adapted to be energized by the current sent through said circuit and to be operated by such current so as to render the last mentioned pair of indicating contacts inoperative only when such current is sufficient for operating the first mentioned electromagnetic device. 120

ling contacts, an electric circuit including said generator and said electromagnetic device and adapted to be completed, by contact of said contacting means with said controlling contacts, so as to operate said electromagnetic device and thereby to render said indicating contacts operative, a second pair 5 of indicating track contacts, contacting means carried by said train and adapted to come into contact with said second pair immediately after, and to be in contact therewith while, the aforesaid contacting means effects contact with said controlling contacts, a switch adapted to be set in two positions in one of which it is and in the other of which it is not, adapted to render operative said second pair of indicating contacts, a second switch adapted normally to be in a position in which it is adapted to render said second pair of indicating contacts operative, a second electromagnetic device included in the aforesaid circuit and adapted to be energized by current sent through said circuit and to be thereby caused, only when said current is sufficient for operating the first mentioned electromagnetic device, to set the first mentioned switch in the position in which it is not adapted to render said second pair of indicating contacts operative, and a third electromagnetic device directly connected between said controlling contacts and adapted to be energized by current sent therethrough and while so energized to hold said second switch in a position in which it is not adapted to render said second pair of indicating contacts operative.

7. Train protecting apparatus comprising a pair of controlling track contacts, a pair of indicating track contacts located remote 40 from said controlling contacts, a generator of electricity, an electromagnetic device adapted when operated to render said indicating contacts operative, contacting means carried by a train and adapted to effect contact with said controlling contacts, an electric circuit including said generator and said electromagnetic device and adapted to be completed, by contact of said contacting means with said controlling contacts, so as 45 to operate said electromagnetic device and thereby render said indicating contacts operative, a second pair of indicating track contacts, contacting means carried by said train and adapted to come into contact with said second pair, electromagnetic danger indicating apparatus carried by said train and adapted to be connected, by the secondly mentioned contacting means, in circuit with said second pair of indicating track contacts, and electromagnetic means included in said circuit in series with said electromagnetic device and adapted to render said second pair inoperative if, when said train is 55 in contact with said controlling contacts, 60 current sufficient for operating said electro-

magnetic device passes through said circuit, said electromagnetic means being adapted to come into operation to render said second pair inoperative before said electromagnetic danger indicating apparatus is adapted to 70 become operated by said second pair rendered operative.

8. Train protecting apparatus comprising a pair of controlling track contacts, a pair of indicating track contacts located remote 75 from said controlling contacts, a generator of electricity, an electromagnetic device adapted when operated to render said indicating contacts operative, contacting means carried by a train and adapted to effect contact with said controlling contacts, an electric circuit including said generator and said electromagnetic device and adapted to be completed, by contact of said contacting means with said controlling contacts, so as 80 to operate said electromagnetic device and thereby to render said indicating contacts operative, a second pair of indicating track contacts, a second electromagnetic device included in said circuit in series with the first mentioned electromagnetic device and adapted to be energized by the current sent through said circuit and to be operated by such current so as to disconnect electrically 85 the last mentioned pair of indicating contacts from each other only when such current is sufficient for operating the first mentioned electromagnetic device, electromagnetic means carried by, and controlling the production of danger indications on, said 90 train, and contacting means carried by said train and adapted to come into contact with said second pair of indicating contacts immediately after the aforesaid contacting means effects contact with said controlling 95 track contacts and thereby to effect connection between said electromagnetic means and said second pair of indicating contacts, said electromagnetic means being adapted to produce a danger indication on said train, 100 when the last mentioned indicating contacts are electrically connected with each other.

9. Train protecting apparatus comprising a pair of controlling track contacts, a pair of indicating track contacts located remote 105 from said controlling contacts, a generator of electricity, an electromagnetic device adapted when operated to render said indicating contacts operative, contacting means carried by a train and adapted to effect contact with said controlling contacts, an electric circuit, including said generator and said electromagnetic device and adapted to be completed, by contact of said contacting means with said controlling contacts, so 110 to operate said electromagnetic device and thereby to render said indicating contacts operative, a second pair of indicating track contacts, a second electromagnetic device included in said circuit in series with the 115

contacting means effects contact with said controlling track contacts and thereby to effect connection between said electromagnetic means and said second pair of indicating contacts, said electromagnetic means being adapted to produce a danger indication on said train, when the last mentioned indicating contacts are electrically connected with each other.

- 10 12. Train protecting apparatus comprising a pair of controlling track contacts, a pair of indicating track contacts located remote from said controlling contacts, a generator of electricity located on a train, an electromagnetic device adapted when operated to render said indicating contacts operative, contacting means carried by said train and adapted to effect contact with said controlling contacts, an electric circuit including said generator and said electromagnetic device and adapted to be completed, by contact of said contacting means with said controlling contacts, so as to operate said electromagnetic device, a second pair of normally operative indicating track contacts, contacting means carried by said train and adapted to come into contact with said second pair immediately after, and to be in contact therewith while, the aforesaid contacting means effects contact with said controlling contacts, and an electromagnetic device electrically connected directly between said controlling contacts and adapted, when operated by current sent out from the generator of said train effecting contact with said controlling contacts, to render the last mentioned pair of indicating contacts inoperative during contact of said train with said second pair of indicating contacts.

40 13. Train protecting apparatus comprising a pair of controlling track contacts, a pair of indicating track contacts located remote from said controlling contacts, a generator of electricity located on a train, an electromagnetic device adapted when operated to render said indicating contacts operative, contacting means carried by said train and adapted to effect contact with said controlling contacts, an electric circuit including said generator and said electromagnetic device and adapted to be completed, by contact of said contacting means with said controlling contacts, so as to operate said electromagnetic device, a second pair of indicating track contacts normally electrically connected together, an electromagnetic device electrically connected directly between said controlling contacts and adapted, when operated by current sent out from said train effecting contact with said controlling contacts, to disconnect electrically the last mentioned pair of indicating contacts from each other, electromagnetic means carried by and

controlling the production of danger indications on, said train, and contacting means carried by said train and adapted to come into contact with said second pair of indicating contacts immediately after, and to be in contact therewith while, the aforesaid contacting means effects contact with said controlling track contacts and thereby to effect connection between said electromagnetic means and said second pair of indicating contacts, said electromagnetic means being adapted to produce a danger indication on said train, when the last mentioned indicating contacts are electrically connected with each other. 70

14. Train protecting apparatus comprising a pair of controlling track contacts, a pair of indicating track contacts located remote from said controlling contacts, a generator of electricity located on a train, an electromagnetic device adapted when operated to render said indicating contacts operative, contacting means carried by said train and adapted to effect contact with said controlling contacts, an electric circuit including said generator and said electromagnetic device and adapted to be completed, by contact of said contacting means with said controlling contacts, so as to operate said electromagnetic device, a second pair of indicating track contacts normally electrically connected together, an electromagnetic device 95 electrically connected directly between said controlling contacts and adapted, when operated by current sent out from said train effecting contact with said controlling contacts, to disconnect electrically the last mentioned pair of indicating contacts from each other, electromagnetic means carried by and controlling the production of danger indications on said train, and contacting means carried by said train and adapted to come into contact with said second pair of indicating contacts immediately after, and to be in contact therewith while, the aforesaid contacting means effect contact with said controlling track contacts and thereby to effect connection between said electromagnetic means and said second pair of indicating contacts, said electromagnetic means being adapted to produce a danger indication 110 on said train, when the last mentioned indicating contacts are electrically connected with each other, and to maintain said danger indication when said train has passed out of contact with said indicating contacts. 115

In testimony whereof I have signed my name to this specification in the presence of two subscribing witnesses.

ARTHUR REGINALD ANGUS.

Witnesses:

M. J. CANDRICK,
I. EASTON.
